UNITED STATES PATENT OFFICE.

HERMAN WALDMAN, OF CHICAGO, ILLINOIS.

DESIGN FOR A DESK SET.

Application filed August 30, 1928. Serial No. 27,987. Term of patent 3½ years.

To all whom it may concern:

Be it known that I, HERMAN WALDMAN, a citizen of the United States, residing at 2738 West Van Buren Street, Chicago, Illinois, have invented a new, original, and ornamental Design for Desk Set, of which the following is a specification, reference being had to the accompanying drawing, forming part thereof.

The drawing shows a perspective view of the desk set showing my new design.

I claim:

The ornamental design for a desk set as shown.

HERMAN WALDMAN.
